PUMP

Harry E. La Bour, Elkhart, Ind.

Application November 18, 1937, Serial No. 175,187

16 Claims. (Cl. 103—113)

This invention relates to self-priming centrifugal pumps of the internal compensating or hydraulic balance type, and constitutes an improvement upon my prior pump of Patent No. 1,578,236 and of my copending application, Serial No. 118,032, filed December 29, 1936.

In the prior patent aforesaid I have disclosed the broad idea of internal compensation or automatic and inherent institution of the priming action, that is, pumping air by recirculation when the impeller is not supplied with sufficient liquid at the normal intake to make up a full discharge, and for automatic and inherent stoppage of internal circulation,—that is, the priming action,—when the impeller receives its full complement of liquid.

In the embodiment of the invention shown in the aforesaid patent, two separate passageways are employed, that is, a main discharge passageway and an auxiliary or priming passageway. Also, in that embodiment, the impeller sweeps the casing and the impeller blades are substantially straight for best operation. While that particular form of pump has very effective priming action, that is, it has the ability to draw and maintain a very high vacuum, and while it is suitable for fairly high fluid heads, it involves a rather expensive construction and takes up a relatively large amount of space.

30 The pump shown in my aforesaid application also embodies the principle of inherent compensation to shift its operation from a recirculation for priming to a straight discharge on liquid pumping.

35 For certain classes of work, particularly for large volume and moderate or low heads, the volute type of casing, with curved blades, is desirable. This type of construction is also desirable where entrained solids are encountered.

40 However, it has been found difficult to get an orderly reintroduction of the priming water into the impeller because of the peripheral position of the volute in respect to the impeller. It is therefore more difficult to secure the same effectiveness in priming, particularly at high lifts or 45 vacuums, as in the pump employing the two distinct and separate passageways.

The essence of the fundamental method of priming according to said prior patent is the introduction of the priming liquid, during priming, at a point where reversal of hydraulic pressure occurs upon the pump receiving its full complement of liquid. Now the more sharp and definite this region and action can be made, the more efficient is the priming action over a range

of speeds and lifts. Also, it is to be observed that the efficiency of the priming action is dependent upon the degree in which the entrained gas is eliminated in the separator and liquid free of such gas is returned into the impeller for priming. The more definite the control of the reintroduction of gas freed liquid, the better will be the operation of the pump.

The chief object of the present invention is to provide a structure which will have the advantages of the volute form of pump, together with the advantages of the two-throat action of the pump shown in my prior patent.

A further object of the present invention is to produce a compact form of self-priming centrifugal pump suitable for general utility. A further object is to provide such a pump having large self-cleaning passageways and at the same time having an improved priming action whereby it can approximate the performance of the earlier form of pump having the two separate passageways.

A more specific object of the invention is to provide a self-priming pump of the volute type with an improved throat arrangement for improving the effectiveness and efficiency of priming and to enable the pump to attain relatively high suctions quickly and easily.

A characteristic of the preferred embodiment of the present invention is the employment of a volute provided with a cut-off and the unidirectional flow of fluid out of the end of the volute that is beyond the cut-off. This insures an orderly or organized flow of fluid in the priming circuit. The inflowing priming liquid is introduced under the main stream of mixture which hugs the periphery of the volute. As soon as this incoming stream of water engages the rapidly moving blades, it is divided into two parts. One part enters the impeller to form the working medium which carries entrained gas and, by the action of the impeller, acquires sufficient energy to provide the necessary flow and discharge pressure. The other part is rejected by the impeller at the cut-off, and is added to the mixture discharge coming out of the end of the volute.

While I speak of unidirectional flow, it is to be understood that there may be variance from continuous flow or even flow in one direction at this point, because of the rotating impeller blades, particularly at the lower speeds. This variation from strict uniformity is particularly the case with flow at the priming opening. The number, inclination and speed of the impeller

blades determines the fluctuations of pressure which occur at this point. However, the flow is definitely organized and directed, in the present pump, and this presents a distinct advance in pumps of this class.

A further object of the present invention is the provision of an improved form of separator and the action which occurs therein, particularly looking to the establishment of a so-called dead pocket. By the term "dead pocket" I intend to convey the idea of a region wherein the liquid is relatively remote from liquid carrying air, so that the water at that point may carry a minimum amount of air. This dead pocket, in the present structure, is located back of the volute extension and constitutes a region into which the flow at high velocity expands into a relatively low velocity region after active separation by kinetic effect has had an opportunity to occur, yet there is still sufficient velocity to prevent accumulation of solids.

A further object of the present invention is to improve and simplify the mechanical construction for ease in manufacture, assembling and servicing, together with low cost of production.

Now in order to acquaint those skilled in the art with the manner of constructing and operating a pump embodying the present invention I shall describe, in connection with the accompanying drawings, a specific form of the same.

In the drawings:

Figure 1 is a vertical cross section axially of a pump embodying my invention;

Figure 2 is a vertical cross section taken on the line 2-2 of Figure 1;

Figure 3 is a top plan view on a reduced scale; and

Figure 4 is a front elevational view with a part broken away to reveal the detail.

Referring first to Figure 1, the pump herein shown comprises the following main parts: 1 is the main frame casting including a pump barrel and various subdivisions later to be referred to. The second main part is the impeller 2. The third main part is the removable gland structure 3. The fourth main part is the closure member 4 for closing the pump barrel, and the fifth main part is the cover plate 5.

The main frame casting 1, in its lower end, defines a pump barrel which includes the back plate 6 and the integral volute 7, the terminal portion of which I designate as the volute extension 8. This pump barrel further includes the cut-off 9 which extends across the full width 55 of the blades of the impeller 2 and has mechanical clearance only with the tips of the blades 10-10 of the impeller 2. The volute extension 8 terminates in an opening 12 and in the side walls 60 of the volute extension 8 there are the priming passageways or openings 13-13, (see Figure 1). A circumferential wall 14 extends laterally, that is, to the left in Figure 1, from the volute 7 and defines a circular opening which is closed or 65 plugged by the closure member 4. The closure member 4 comprises the generally cylindrical wall 15 which extends inwardly and carries at its inner end the front plate member 16. This front plate member 16 has the intake opening 17 through which the incoming stream of fluid is 70 supplied to the impeller 2. The flared conical wall 18 provides, in conjunction with the wings 20 of the blades of the impeller, for an inlet pocket 19 to facilitate the entry of liquid into the impeller.

The cover member 5 has a peripheral shoulder

22 which engages the margins of the opening in the wall 23. This shoulder 22 has, in the form herein shown, a metal-to-metal engagement, which, since it is an internal joint, need not be absolutely fluid-tight, but preferably should be as tight as it is conveniently possible to make it. The cover member 4 has an integral extension 24 herein shown as of convex shape which is provided with a number of openings 25-25 to form a strainer. This strainer is shown as integral with the closure member 4 but obviously it may be made, for convenience of construction, as a separate part or integral, as desired. A hollow boss 26 formed in the central part of the strainer 24 is provided to receive the compression spring 27 and the bolt 28, the bolt 28 having a head at its outer end and a retaining pin or equivalent fastening means at its inner end. The compression spring 27 may be suitably pre-stressed so that the desired pressure upon the strainer 24 and hence upon the closure member 4, to hold it in place, may be secured by a very small displacement of the pin 28 when the cover plate 5 is fastened in place.

The back plate 6, which is an integral part of the main frame or casting 1, has a recess machined at the center thereof for receiving the flange 29 of the removable packing gland cartridge 3. This removable packing gland cartridge 3 is held in place by stud bolts 30 which may be released from the back side of the pump. This removable packing gland cartridge is accessible from the rear of the pump for servicing and is removable through the main bore of the pump barrel, as will be described later. A mounting ring 32 for the take-up bolts 33 of the gland follower 34 is held under the stud bolt 30 to the back plate 6.

The particular arrangement of packing in the packing gland 3 is not essential and various forms of packing may be provided within the scope of the present invention so long as the cartridge is removable, as indicated, through the main bore, whereby the entire pump may be taken apart from the front of the pump without disturbing its mounting or the suction and discharge connections.

As shown, the removable packing gland cartridge provides an annular recess for fibrous or other packing 34. An intermediate member 35 acts as a follower for the packing 34 and has a central recess for the introduction of grease to lubricate the packing, and it, in turn, is packed by fibrous or the like packing 36 and engaged by the gland follower 31, which is tensioned through the medium of a suitable spring or set of springs 37 and wing nut 38 on the bolt 33.

The main body or casting 1 is supported upon a suitable support which, in the present instance, comprises a rearwardly extending flange 40 having a shoulder 41 seated in a corresponding rabbet or recess in the mounting bracket 42. This mounting bracket 42 is annular in shape and has the mounting flange or bell 43 for connection to the frame of the electric motor or bell housing (that is, the flywheel housing) of a gas engine or the like. A bracket 45 under the main body 1 provides additional support for taking the weight of the pump off of the mounting bracket 42. The integral flange 40 may have an extension for securing a suitable mounting bracket or a mounting bracket of different form may be clamped to the flange 40, or otherwise arrangements may be made for supporting or steadyng the pump in the desired position.

The impeller 2 has an operating shaft 46 which, in the present construction, is shown as an independent or separate piece fastened to the central hub 47 by a threaded extension and nut 48, the shaft being kept from turning in the hub 47 as by a Woodruff key or the like. Obviously, instead of a separate shaft the impeller and shaft may be constructed of one casting or otherwise made unitary.

10 The shaft 46 may be connected in any suitable manner to the shaft of the driving motor. Thus, for example, if the shaft is to be connected to an internal combustion engine a disc may be fastened, as by welding or the like, to the right-hand end of the shaft and said disc then clamped to the flywheel of the engine, whereby the shaft 46 is supported from the bearings of the engine and need not be self-supporting in the pump. One manner of supporting the impeller shaft on 15 the separate set of bearings is shown in my Patent No. 1,993,999.

The main frame casting 1 comprises, in addition to the pump barrel aforesaid, two other main parts, namely, the separator 47 and the intake trap 48. The separator 47 has a clamping flange 49 at the top thereof for the connection of the companion flange 50 of a discharge pipe 52. The discharge opening 53 from the separator 47 faces upwardly, whereas the intake opening 54 for the trap 48 opens horizontally. A clamping flange 55 for cooperation with companion flange 56 of the intake or suction pipe 57 is formed integrally with the walls of the trap 48. The discharge chamber 47 is of generally cylindrical form, slightly flattened in a vertical direction, as may be seen from Figure 2. The back wall or head 58 extends down through the back plate 6, leaving a channel 59 between the said head or back wall and the side wall of the volute 30 extension 8. The channels are preferred, but a single large channel might be used. It is to be observed that the shape of the separator 47, while cylindrical in outline, is wedge-shaped in plan, as may be seen from Fig. 3. The back wall 58 and the intermediate wall 23 are inclined towards each other in the direction in which the volute extension 8 discharges fluid. The issuing stream of fluid from the volute extension 8 strikes the circular wall 61 and is 35 directed upwardly in the separator to give the gas which is entrained during priming an opportunity to free itself from the liquid, and the liquid then rises and flows back to the rear of the volute extension 8, where the casing is wider, as will be seen from Figure 3, and the region indicated by the reference character 60 thereby constitutes the dead pocket where there is the greatest proportion of liquid freed of gas, and from there to supply, through the priming ports 40 13-13, a stream of priming fluid going to the impeller. While the back wall 58 and intermediate wall 23 are inclined towards each other, the front wall 62 lies substantially at right angles to the axis of the impeller shaft, as does the 45 mounting flange shoulder 41 (see Figure 1). The intake trap 48 may, in outline, substantially overlie, or register with, the separator and at its lower end this separator has a narrow portion which overlies, or registers with, the 50 pump barrel and forms an extension of the same. The wall 63, which defines the bottom of the intake trap, is cylindrical in shape and forms an extension of the pump barrel. A groove 64 is formed in the bottom wall to receive a projection or stud 65 formed on the closure mem-

ber 4, to insure application of the closure member 4 in a definite position, and to prevent accidental rotation. The cover plate 5 overlies the circular opening 66 which is formed in the front wall 62, and this cover plate 5 is held in place by suitable stud bolts 67 which are shown in Figures 1 and 4.

Obviously, if desired, the intake trap may be made of the same width as the barrel portion throughout its vertical height, or may be otherwise shaped if so desired. However, it is quite advantageous to have the intake trap of the shape and configuration shown, so that it may retain a maximum of liquid upon the reflux of liquid upon stopping the pump and the carrying of air through the separator and intake trap to break the vacuum in the suction pipe 57. By having the main part of the intake trap disposed above the opening 17 in the front plate 16, it can be seen that a maximum charge of liquid will be retained when the air strikes back through the separator, through the pump, and through the opening 17 into the intake trap. Thus no check valve is required in this form of pump and yet ample liquid is retained for priming.

A removable plug 69 is provided on the separator for charging the pump body with liquid to initiate operation. Draining plugs 70 and 72 permit draining of all parts of the pump when it is desired to remove the liquid therefrom.

The assembly and servicing of the present pump is facilitated by the aforesaid structure. The main body member 1, including the pump barrel, back plate, supporting flange, the separator and the intake trap, are all formed in one casting. This greatly facilitates construction. The machining of the main frame can be accomplished on a boring mill or the like on a single axis. That is to say, the supporting shoulder 41 for the bracket, the recess 29 for the removable packing gland cartridge, the cylindrical surface of the cut-off 9, the bore of the barrel which is fitted by the closure member 4, and the opening 66 in the front wall, are all coaxial and may be very simply machined. The supporting bracket 42 is of simple circular construction, easily finished by machining and drilling. The closure member 4 and the cover member 5 likewise are finished by turning on a lathe, or the equivalent.

In assembly, the pump is of the greatest simplicity. The impeller and packing gland cartridge may be inserted as a unit and removed as a unit, or, if desired, the impeller may be removed from the shaft 46 and likewise the packing gland cartridge removed from the shaft through the front opening. The member 4 and the cover plate 5 may be removed and replaced readily without disturbing other parts. Obviously, the details of construction may be varied, that is, for example, the screen 24 may be made a separate part from the closure member 4 and it may be supported on the cover plate 5, if desired.

The operation of the pump is as follows: assume that the pump has been charged with sufficient liquid to constitute a working charge. Assume that the liquid stands at the same level in the separator and the trap and the shaft 46 is rotated. Liquid will first be drawn out of the trap, down to substantially the bottom of the opening 17 in the front plate 16, and discharged into the trap through the volute extension 8 by way of opening 12 and openings 13.

It will be observed that the volute extension 8 does not continue on the same rate of increase as

does the main body of the volute, for the reason that the openings 13 constitute additional outlets during the time of liquid pumping. Furthermore, by this construction, the issuing stream of mixture is subjected to an intensified centrifugal effect within the volute extension, i. e., a more pronounced change of direction, and this stream tends, therefore, to hug the outer periphery of the passageway or channel. In the particular construction illustrated the bottoms of the openings 13 are disposed at approximately the periphery of the blade tips, whereby liquid flowing in through the openings 13-13 tends immediately to come under the influence of the pressure conditions within the rotating impeller.

The cut-off 9 is shown as disposed slightly below the level of the top of the impeller travel, although this is not essential, and it is disposed beyond the openings 13, considered in the direction of travel of the blade tips and of the fluid flow. Instead of two openings 13, one large opening at one side only might be employed.

The curved blades tend to move the liquid tangentially and radially. By control of the curvature of the blades the ratio of radial throw to circumferential throw may be controlled and the ratio of pressure to volume or delivery may be suitably selected.

Assuming that the priming operation is initiated by the rotation of the impeller in a clockwise direction as viewed in Figure 2, the blades 10-10 tend to throw the contained liquid radially and circumferentially, discharging the same through the opening 12 of the volute extension 8 and to discharge any excess through the openings 13. As soon as the impeller casing has been substantially emptied of liquid, air takes its place and, since the density of air is so much less than the density of water or other liquid which is normally pumped, the pressure developed by the rotating blades will be insufficient to overcome the gravity tendency of the water to flow back into the impeller chamber. Hence, liquid will tend to flow into the openings 13 into contact with the revolving blades, and liquid also tends to enter the opening 12 and flow back into the space occupied by the impeller.

If the head of liquid is insufficient to force liquid sufficiently far into the impeller to secure a denser working medium than air, and of a volume sufficient to establish an orderly flow, the pump may exhibit the well known action of low vacuum or starting stall. The present construction of pump exhibits substantially no tendency to stall at this point, but immediately begins to form a working fluid more dense than air and less dense than liquid, by the inflow of liquid through the openings 13 into contact with the impeller. The pressure upon the front faces of the blades 10-10 is that due to the rapidly rotating blades working against the liquid which is moving more slowly, or which may be substantially stationary at this point. The pressure upon the back sides of the blades 10-10 is below the mean pressure in the impeller chamber just as the pressure upon the advanced faces tends to be above.

Liquid flowing in through the openings 13 and engaging the impeller blades or tending to drop into the space between them is divided into two parts by the action of the impeller, and the cut-off 9. The impeller tends to throw the liquid radially outwardly about its entire periphery as it rotates and hence any liquid carried by, or

operated upon by the impeller blades, tends to be thrown to the periphery of the channel or volute passageway 11, and where, as in the case of priming, the charge of liquid is insufficient to completely fill the volute channel 11, the space between adjacent blades as the same approaches the passageways 13 gives room and a pressure reduction which tends to draw the liquid from the separator through the ports or passageways 13 into the interior of the impeller 10 to form a working mixture. The liquid so drawn in is mixed or churned up with air and is discharged as a stream which hugs the outer periphery of the volute passageway 11 and is driven out through the opening 12. The priming liquid which is admitted through the openings 13 into contact with or under the influence of the impeller, enters below the issuing stream of mixture and such part of the entering stream of priming liquid as can be taken into the impeller is so taken in, but that part of the liquid which is engaged on the front sides of the blades as the blades approach the cut-off 9 is rejected by the impeller at this point and forms a stream which slides over the top edge of the cut-off 9 and follows the wall 51 upwardly. Thus, out of the opening 12, during priming, there are two distinct flow streams, first, the flow stream of mixture which hugs the outer wall of the volute channel 11 and passes through the opening 12 into the separator above the openings 13 or the major part of the same, and the second flow is that which is rejected by the impeller over the cut-off 9 and follows up the wall 51. The issuing stream of mixture is thus bent upwardly by the adjacent walls of the separator and by the stream of rejected liquid, and it flows upwardly along this curved wall, tending to agglomerate the bubbles and free them by the action in the separator. The practical effect of these two streams is to form an outward unidirectional flow of fluid (liquid and gas mixture) at all times during priming. Thereby the opening 12 is filled with outwardly flowing fluid and hence none of the heavy gas laden liquid can be sucked back into the impeller. By this arrangement an orderly flow of priming liquid which is largely freed of gas is provided and as a consequence the pump primes more rapidly and is able to attain higher suctions than would be the case if heavily gas laden liquid could reenter the impeller.

The action in this separator is unique. The stream of fluid issuing from the end 12 of the volute comprises, first, the rejected priming water, which flows at fairly high velocity due to the fact that it has been directly under the influence of the blades. Second, there is the issuing stream of mixture which is more remote from the influence of the blades. These two streams are not readily distinguishable and by the time they issue and strike the wall 51, they are merged. Following the curved wall 51 the velocity at the narrowest part (the right in Figure 2) is a maximum and hence kinetic or centrifugal action is brought into play, tending to squeeze out and agglomerate the entrained bubbles of air. Then the stream flows upwardly to the left and down into a gradually enlarging space and lowering its velocity, with the result that the bubbles of air gravitate out and escape by opening 53. The action in the separator is vigorous and effective. The stream of mixture is deeper and narrower at the right of Figure 2 and becomes thinner and wider as it approach-

es the dead pocket 60. The dead pocket is by no means a quiet body or region, but only relatively so. Liquid substantially freed of gas flows along the two sides of the volute extension in the channels 59—59 through the openings 13, and again into the impeller. This action of the travel of the liquid in a path which may be described roughly as a figure 8, clockwise in the impeller chamber and counterclockwise in the separator, 10 with a crossing of the two streams at the volute extension 8, proceeds until the vacuum is high enough to pull water over through the suction pipe 57 or to draw as high a dry vacuum as the pump is capable of exerting in case liquid is not 15 available. When liquid comes over through the suction pipe 57 and supplies liquid by way of the opening 17 to the central part of the impeller, the density of the working medium which the impeller operates upon is immediately increased 20 and the discharge pressure is thereby likewise increased, and evacuation is then quickly completed to the point where a flow of liquid only enters through the opening 17 and is discharged through the volute channel 11 and the volute 25 extension 8 through both the openings 13, to handle the full complement of liquid on discharge. Due to the reversal of pressure occurring at the ports 13, the tendency for solid material to lodge is counteracted. Likewise, the 30 flow along the channels 59—59 at each side of the volute extension 8 and over the same is quite rapid at all times, whereby any tendency for the deposit of solid material and debris is overcome, the same being expelled through the opening 53 35 with the water being pumped.

Any material which is capable of passing through the strainer openings 25 can be handled by the pump, and material which cannot pass the strainer openings 26 is held in the bottom part 40 of the intake trap, from which it may be removed by opening the cover plate 5. The openings in the strainer 25 present a much greater aggregate than the opening 17 and hence partial clogging of the same will not stop the operation of the pump.

I do not intend to be limited to the precise forms or details herein disclosed, except as called for by the appended claims, as the disclosure herein is illustrative, rather than limiting.

I claim:

1. A self-priming centrifugal pump comprising an impeller chamber having a cutoff and a volute extending over the cutoff, an impeller cooperating with said cutoff and said volute, a separator having a curved end wall leading from the cutoff for receiving and leading the liquid passing out of the volute and over the cutoff in a curved path from a substantially horizontal direction to substantially a vertical direction, the separator having a bottom wall substantially in line with the cutoff and the end of the volute extending into the separator above said bottom wall, the separator having a lateral wall which is spaced away from a side of the volute and a sidewall of the volute having a transverse opening communicating with the inside of the separator adjacent the bottom wall for leading priming liquid from the separator into the impeller in advance of the cutoff.

2. A self-priming centrifugal pump comprising an impeller casing having a cutoff and a volute of progressively increasing cross section, an impeller having a plurality of backwardly curved blades cooperating with the cutoff and

with the volute, the volute having a portion extending beyond the cutoff to direct and be filled during priming by the stream of mixture and the priming liquid rejected by the cooperation of the impeller and the cutoff, and a separator within which the said extending portion is disposed, there being a passageway formed through a side wall of said extension in advance of the cutoff for the introduction of priming liquid from the separator into contact with the impeller, said passageway being subjected to pressure of liquid being pumped when the impeller receives a full complement of liquid sufficient to produce outflow whereby said passageway tends to clear itself of entrained solids.

3. A pump comprising an impeller casing having a volute, an impeller in said casing cooperating with said volute, a separator, a portion of the volute projecting into and terminating within the separator above the bottom wall thereof, said separator having a wedge shape with the narrower part thereof facing the discharged end of the volute and the wider part behind the projecting portion of the volute to form a dead pocket of minimum velocity during priming.

4. In a pump, a body casting having a pump barrel at its lower end and a pair of chambers thereabove constituting an intake trap and a separator, a transverse bore in the lower part of said casing extending into the pump barrel, the bore on the back side being closed by an integral backwall having a central opening, a packing gland secured to the back wall and removable through said bore, an impeller insertable through said bore and having a shaft extending through said gland, a circular intake member forming a front wall for the impeller and having an inlet opening, a strainer member extending forwardly of the intake member, a cover plate closing the outer end of the bore.

5. In a pump a body casting comprising a pump barrel including a back plate and a volute, integral extensions defining a hollow body and comprising a front intake trap wall, a back separator wall and an intermediate dividing wall back of which lies a separating chamber and in front of which lies an intake trap, there being concentric openings through the front wall and the intermediate wall and through the backplate, a circular intake member having a cylindrical pluglike portion for closing the opening in the intermediate wall, and having a front plate portion with a central intake opening, an impeller disposed between said back plate and said front plate portion and cooperating with the volute portion of the pump barrel, a shaft for the impeller extending through the back plate wall, said impeller being removable through said concentric openings in the intermediate wall and the front wall, and a cover plate for the opening 60 in the front wall.

6. In a pump, a pump barrel member comprising an integral volute, back plate and vertical walls defining a separator communicating with the outlet of the volute and having its side walls spaced from the sidewalls of the volute, and an intake trap which lies partly in front of and partly above the pump barrel, an opening extending through the trap concentric with the pump barrel, an impeller disposed in the barrel and cooperating with the volute, said impeller being removable axially through said concentric opening, a circular closure member for the pump barrel, said member having a front plate for the impeller and having a central in-

take opening, a strainer member extending over the front plate, and a closure plate for the opening through the front trap wall.

7. The combination of claim 6 combined with 5 a separable packing gland cartridge removable through the pump barrel, and a circular mounting extension, surrounding the removable packing gland cartridge.

8. In a pump, a pump barrel comprising a 10 volute and back plate, a mounting extension integral with the back plate, an intake chamber having walls integral with the pump barrel and having an opening concentric with the pump barrel, a circular closure member for the pump 15 barrel comprising a front plate for the impeller, said front plate having an inlet opening, an impeller removable through the barrel and the concentric opening disposed between the back plate and the front plate, said closure member 20 bearing a strainer member, a cover plate for the concentric opening in the intake chamber and compression spring means between the cover plate and the strainer member.

9. In a pump, a body comprising a pump barrel with integral front and back walls rising above the pump barrel and defining a wedge-shaped separator chamber disposed wholly above the pump barrel, and an intake trap disposed in front of and above the pump barrel, the pump 30 barrel comprising an integral back plate and a volute, the volute having a terminal portion which extends into the lower part of the separator and has its discharge directed into the narrow portion of the wedge shaped separator, 35 there being an opening through the trap to the pump barrel, a closure member bearing a front plate for closing the pump barrel and having a central inlet opening, a cover plate for the outer end of said trap opening, and means disposed 40 between the cover plate and the closure member for holding the closure member in seated position.

10. In a pump of the class described, a main body member comprising a pump barrel portion having a front opening and an encircling volute 45 portion, an impeller adapted to be inserted through said barrel opening, a closure member for the opening forming a front plate for the impeller, said front plate having an intake opening, said main body member having walls defining a separator of generally cylindrical outline disposed above the pump barrel and being of a diameter substantially greater than the pump barrel and of an axial depth approximately equal 50 to that of the pump barrel, and an intake trap lying at its upper end against the separator and being of substantially the same outline and at its lower end forming substantially a continuation of the pump barrel whereby the major part of the 55 capacity of the intake trap is above the pump barrel.

11. In a pump of the class described, a main body member comprising a pump barrel portion having a front opening and an encircling volute 60 portion, an impeller adapted to be inserted through said barrel opening, a closure member for the opening forming a front plate for the impeller, said front plate having an intake opening, said main body member having walls defining a separator of generally cylindrical outline disposed above the pump barrel and being of a diameter substantially greater than the pump barrel and of an axial depth approximately equal to that of the pump barrel, an intake trap lying at its upper end against the sep- 65

arator and being of substantially the same outline, and at its lower end forming substantially a continuation of the pump barrel, whereby the major part of the capacity of the intake trap is above the pump barrel, the lower end of the intake trap having an opening registering with the opening in the pump barrel for removal of the cover member and the impeller from the pump, and a cover plate for closing the opening in the lower end of the separator. 10

12. In a pump of the class described, a main body member comprising a pump barrel portion having a front opening and an encircling volute portion, an impeller adapted to be inserted through said barrel opening, a closure member for the opening forming a front plate for the impeller, said front plate having an intake opening, said main body member having walls defining a separator of generally cylindrical outline disposed above the pump barrel and being of a diameter substantially greater than the pump barrel and of an axial depth approximately equal to that of the pump barrel, an intake trap lying at its upper end against the separator and being of substantially the same outline and at 25 its lower end forming substantially a continuation of the pump barrel whereby the major part of the capacity of the intake trap is above the pump barrel, the lower end of the intake trap having an opening registering with the opening in the pump barrel for removal of the cover member and the impeller from the pump, a cover plate for closing the opening in the lower end of the separator, and a screen overlying the closure member and being held in place by the 30 cover plate. 35

13. Self-priming pump having a separator and a volute with a volute extension disposed in the separator, said volute having a progressively increasing cross section to the volute extension, 40 said volute extension having openings through the side walls and having a cross section of substantially the same value throughout its length, and a cutoff for the volute disposed beyond said openings in the volute extension. 45

14. In a self-priming centrifugal pump, a separator chamber having at its lower end a slot in a wall thereof, an impeller casing of the volute type joined to the walls of the chamber about said slot, an impeller rotatable in a plane at substantially right angles to said wall and having its periphery projecting into said slot, said volute casing having a cutoff at one end of the slot, a hoodlike volute extension extending from the other end of the slot and directing the stream 55 of mixture from the volute over the cutoff, said volute extension having a peripheral wall for guiding the mixture radially far enough away from the periphery of the impeller to produce a region of reduced pressure between said guided stream of mixture and the cutoff, said volute extension having side walls disposed at the sides of the slot, and slots formed in said side walls at said region of reduced pressure for permitting the entry of priming liquid directly from the lower end of said separator into engagement with the periphery of the impeller in advance of said cutoff, said priming liquid engaged by the periphery of the impeller at said region of reduced pressure being divided by said cutoff whereby part enters the impeller casing to form a mixture and a part is rejected and flows along with said issuing stream of mixture over the cutoff. 60

15. A self-priming centrifugal pump of the volute type comprising a gas and liquid sepa- 70 75

rator, an impeller, an impeller housing provided with a cutoff, and a volute having a terminal portion extending over the cutoff to define a discharge outlet leading to the separator, there being a priming opening in the side of the volute in advance of said terminal portion, said opening lying at substantially the same radius as the periphery of the impeller and being disposed in advance of the cutoff for admitting priming liquid from the separator into the periphery of the impeller in advance of the cutoff, said discharge outlet being substantially completely filled with outwardly flowing fluid during priming to prevent sucking back of liquid heavily laden with gas.

16. A self-priming centrifugal pump of the volute type comprising an impeller chamber having a cutoff, an impeller having mechan-

ical clearance only with the cutoff, a volute having a terminal portion cooperating with the cutoff to define a discharge opening and having an intermediate portion in advance of the cutoff spaced radially from the impeller to produce a region of reduced pressure at the periphery of the impeller in advance of the cutoff, there being a passageway from the separator through the side wall of the volute opening into the periphery of the impeller at said region of reduced pressure to admit priming liquid, a part of said admitted priming liquid being rejected over the cutoff and driven out of said discharge opening along with said stream of mixture during priming to prevent sucking back of a part of said stream of mixture.
